Atgys.

UNITED STATES PATENT OFFICE.

LUCIUS E. WEAVER, OF EAST HAMPTON, CONNECTICUT, ASSIGNOR TO SUMMIT
THE READ COMPANY, OF EAST HAMPTON, CONNECTICUT, A CORPORATION OF
MAINE.

SEWING-MACHINE BOBBIN CASE.

1,419,185.

Specification of Letters Patent. Patented June 13, 1922.

Application filed July 15, 1921. Serial No. 484,910.

To all whom it may concern:

Be it known that I, LUCIUS E. WEAVER, a citizen of the United States, residing at East Hampton, in the county of Middlesex 5 and State of Connecticut, have invented new and useful Improvements in Sewing-Machine Bobbin Cases, of which the following is a specification.

This invention relates to a bobbin case, 10 including a body having a central post about which the tubular core of a universally wound bobbin is rotatable, and a bobbin-supporting plate having a core-engaging hub which is rotatable with the bobbin about the 15 central post.

The object of the invention is to provide in a bobbin case of this character, improved means for separably connecting the said plate and its hub with the case body, and 20 for preventing undesirably loose and free rotation of the bobbin-supporting plate and its hub.

The invention is embodied in the improvements hereinafter described and claimed.

25 Of the accompanying drawings forming a part of this specification,—

Figure 1 is a top plan view of a bobbin case embodying the invention, the bobbin being removed.

30 Figure 2 is a view similar to Figure 1, showing the bobbin in place.

Figure 3 is a section on line 3—3 of Figure 1.

Figure 4 is a sectional view of the bobbin.

35 Figure 5 is a section on line 5—5 of Figure 2, certain parts being broken in elevation.

Figure 6 is a sectional view of the bobbin-supporting plate and its hub.

40 Figure 7 is a sectional view of the case body.

Figure 8 shows in perspective the stud and the tapered screw hereinafter described, separated from each other.

45 The same reference characters indicate the same parts in all of the figures.

In the drawings, 12 represents the annular wall or body of a bobbin case, and 13 represents a bottom member, which is preferably a cross-bar extending across the base of the body. In the central portion of the bottom member is formed a socket 14. To the bottom member is fixed an upstanding tubular post 15, the bore of the post being 55 concentric with, and preferably of greater

diameter than the socket 14. 16 represents an annular collar seated on the bottom member 13, and embracing the base portion of the post 15. 17 represents an annular bobbin-supporting plate, adapted to rotate in 60 the bobbin case, and provided with a tubular hub 18, fixed to said plate, and formed externally to engage the core 19 of a universally wound bobbin, the winding of which is shown at 20, the hub preferably having a polygonal 65 external surface adapted to indent the core 19. The bore of the hub 18 is formed to receive and turn on the collar 16, and is provided with an annular internal lip 21, which is spaced from the collar 16, said lip and 70 collar forming opposed spring abutments.

22 represents the head, and 23 the shank of a stud, the head being formed to enter the outer portion of the bore of the hub 18, and bear on one side of the lip 21. The shank 75 23 is tubular, and is longitudinally split at 25. The shank is formed to enter the hollow post 15, and its bore is slightly tapered and provided with an internal screw thread, indicated at 26 (Figure 8). 27 represents a 80 tapered screw formed to enter the bottom member socket 14, and to expand the split shank 23 to cause a frictional engagement between the periphery of the shank and the bore of the hollow post 15. 85

29 represents a spring interposed between the abutments formed by the collar 16 and the lip 21. Said spring acts to press the lip 21 against the stud head 22, and thereby frictionally oppose rotation of the plate 17 90 and hub 18, and the bobbin engaged therewith.

In assembling the parts, the collar 16 is applied to the bottom member 13 and post 15, as shown by Figure 7. The plate 17 and its 95 hub 18 are then inserted in the body 12, the spring 29 having been previously inserted in the bore of the hub. The insertion of the plate and hub into the body causes the compression of the spring between the lip 21 and 100 the collar 16. The stud is then inserted, its head entering the outer portion of the hub 18, and bearing on the lip 21, and its shank entering the post 15. Finally the screw 27 is inserted and expands the split shank 23 105 against the bore of the post 15, the shank being thus firmly engaged with the post. When the parts are assembled, the spring 29 is compressed and presses the hub lip 21 against the stud head 22, so that loose ro- 110

tation of the bobbin-supporting plate and its hub, and of the bobbin engaged with the latter, is prevented.

I claim:

- 5 In a sewing-machine bobbin case, in combination, a case body having a fixed bottom member containing a central socket; a tubular post fixed to said bottom member, the bore of the post being concentric with said socket;
- 10 an annular collar seated on the bottom member and embracing the base portion of the post; an annular bobbin-supporting plate, having a tubular hub fixed to said plate and formed externally to engage the core of a
- 15 universally wound bobbin, the bore of said hub being formed to receive and turn on said collar, and provided with an annular internal lip spaced from the collar, said lip and col-

lar forming opposed spring abutments; a stud having a head formed to enter the hub 20 bore and bear on one side of said lip, and a split tubular shank formed to enter the hollow post, the bore of said shank being tapered and screw-threaded; a tapered screw formed to enter the bottom member socket 25 and expand the shank, to cause a frictional engagement between the latter and the bore of the hollow post; and a spring interposed between the abutments formed by the said collar and lip, and acting to press the said 30 lip against the stud head, and thereby frictionally oppose rotation of the bobbin-supporting plate and its hub.

In testimony whereof I have affixed my signature.

LUCIUS E. WEAVER.
